Jacob Simon, Irvington, and Philip Klein,
Maplewood, N. J.

Application January 25, 1946, Serial No. 125,965

Term of patent 3½ years

(Cl. D86—8)

To all whom it may concern:

Be it known that we, Jacob Simon, a citizen of the United States, residing in Irvington, county of Essex, and State of New Jersey, and Philip Klein, a citizen of the United States, residing in Maplewood, county of Essex, and State of New Jersey, have invented a new, original, and ornamental Design for a Comb, of which the following is a specification, reference being had to the accompanying drawing, forming part thereof.

In the drawing:

Figure 1 is a side elevational view of a comb embodying our new design;

Figure 2 is a front end view thereof; and

Figure 3 is a top plan view thereof.

We claim:

The ornamental design for a comb, as shown.

JACOB SIMON.
PHILIP KLEIN.
